D 16756

UNITED STATES PATENT OFFICE.

FLORENCE KROEGER, OF NEW YORK, N. Y.

DESIGN FOR A CLOCK-CASE.

SPECIFICATION forming part of Design No. 16,756, dated June 22, 1886.

Application filed April 22, 1886. Serial No. 199,855. Term of patent 3½ years.

To all whom it may concern:

Be it known that I, FLORENCE KROEGER, a resident of New York city, in the county and State of New York, have invented and produced a new and original Design for a Clock-Case, of which the following is a specification, reference being had to the accompanying photograph, which represents a perspective view of my new design for a clock.

This invention relates to a new configuration of a clock-case; and it consists in a certain crank-like ornament on the end of the clock-case, as hereinafter shown.

In the accompanying photograph, the letter A represents the body or case of the clock. B is the circular dial, and C an ornamental ring around said dial.

At one end of the case is a crank-shaped ornamental projection, D.

E are corner ornaments on the body of the case A, said ornaments representing conventional flowers and leaves, as shown.

I claim—

The design for a clock-case, the same consisting of the body A, dial B, ornamental ring C, crank-like ornament D, and corner ornaments E, of conventionalized flowers and leaves, substantially as shown.

FLORENCE KROEGER.

Witnesses:
